UNITED STATES PATENT OFFICE

ABELARDO LINÁRES, OF MARACAIBO, VENEZUELA

INTERMITTENT-GRIP DEVICE

Original application filed June 1, 1927, Serial No. 195,810. Divided and this application filed May 1, 1928.
Serial No. 274,283.

This invention relates to intermittent grip devices, and constitutes a division of my original application Serial No. 195,810, filed June 1st, 1927, for screw adjustable mechanisms.

5 From one aspect, a feature of the invention consists in the provision, in combination, of a rotatable element having a ratchet wheel thereon, and a detachably mounted handle member having a cooperating pawl element, 10 said member being demountable from the ratchet wheel for convenience in storage or shipment and being reversible thereon for effecting reverse directions of rotation.

From a related view point, another feature 15 of the invention consists in a sectional arcuate handled head, mounting a pawl and having provision for enlargement and reduction of its enclosing area to embrace and hold or to release and separate from a ratchet wheel, 20 including means for locking its sections in and releasing them from ratchet engaging position.

The construction provided, facilitates and 25 greatly simplifies the ease with which the pawl-carrying head may be attached to and released from engagement with the ratchet wheel, and since, in accordance with the invention, the pawl member is detachable and is formed for reversible connection to the 30 ratchet wheel, it is evident that from this view point, a further feature of the invention resides in the provision in combination with a ratchet member, of a demountable, handled pawl-carrying member cooperating 35 therewith and demountable from and reversible thereon to reverse the direction of rotation imparted to the ratchet member thereby.

The structural features providing these 40 and other advantages are described more fully in the following detailed specification which is to be read in conjunction with the accompanying drawings forming part thereof and in which:—

Figure 1 is a view in side elevation of an 45 intermittent grip device constructed in accordance with the present invention and applied to the threaded adjusting member of a vise structure.

Figure 2 is a longitudinal vertical section 50 through the ratchet head and handled pawl

member taken on the line 2—2 of Figure 1.

Figure 3 is a fragmentary vertical section 55 of the pawl-carrying handled member expanded and removed from the ratchet head.

Figure 4 is a transverse section through the locking ring and handle with the parts in ratchet enclosing position, the section being taken on line 4—4 of Figure 2.

Figures 5, 6, 7 and 8 show in perspective 60 the clamping nut, spring washer, pawl spring and pawl in their order of assembly.

In the drawings, the invention is shown in Figure 1 as applied to a vise structure, 1 representing the tubular shank of the movable jaw of such a structure with the threaded interior surface of which the rotatable threaded sleeve 2 engages to move the shank and its jaw. The sleeve is rotatably mounted on the fixed shank 3 which may be part of the fixed jaw of the vise structure. At its outer end the jaw adjusting threaded sleeve 2 has rigidly connected therewith a ratchet wheel 4 having its periphery curved substantially convexly transversely thereof and formed with a circumferentially spaced series of radial sockets 5. The sleeve 2 is retained on the fixed shank 3 by a suitable retaining nut 6 engaging the threaded end of the shank. The vise structure described is cited as 70 illustrative of the application of the intermittent grip device of the present invention and forms no part thereof, but constitutes in part the subject matter of a copending application, Serial No. 274,282.

The means associating with and providing 75 an intermittent rotating grip on the ratchet wheel 4 comprises a handle bar 7 and a head for embracing the ratchet wheel 4. Said head comprises a section 8 which is integral 80 with the handle bar and a cooperating section 9 having a short shank 10 adapted to fit in a laterally cut away portion 11 (Figure 3) on the adjacent end of the handle bar 7 and connected with the handle bar 7 by a transverse pivot element 12. A retaining ring 13 is slidable on the handle 7 to and from 85 position to overlap the shank 10 and to then retain the shank 10 completely in the cut away portion 11 of the handle 7 so that the sec- 90

tions 8 and 9 will be retained on the ratchet wheel 4 and will partially encircle the ratchet wheel 4. The sections 8 and 9 are curved transversely to conform substantially to the 5 transverse curvature of the peripheral portion of the ratchet wheel 4. The free end of the shank 10 and the adjacent wall of the cut away portion of the handle 7 are complementarily beveled (Figure 3) so as to produce a relatively large contact surface between the handle 7 and the shank 10 when the shank 10 is completely disposed in the cut away portion 11 of the handle 7. The adjacent or abutting ends of the sections 8 and 15 9 likewise are complementarily beveled so as to fit neatly and firmly against each other when the sections 8 and 9 are closed as shown in Figure 2. When the ring 13 has been slid along the handle 7 out of engagement with 20 the shank 10, the section 9 may swing away from the section 8 a distance sufficient to permit removal of the lever from the ratchet wheel 4 as shown in Figure 3.

The section 9 of the head of the lever is 25 formed with an outwardly extending tubular boss 14 having a head 15 at its outer end formed with the laterally extending flange or marginal edge portion 16 and with a relatively small central opening 17 in axial alinement with a larger opening 18 in the section 9. An actuating pawl 19 extends slidably through the opening 18 and has a reduced rigid shank 20 which protrudes from the tubular boss 14 through the opening 17 in 35 the head 15. The outer end portion of the shank 20 is threadedly engaged by an adjusting nut 21 having a laterally extending finger 22 formed with a bent end portion 23 in contact with the edge of the flange 16. 40 A convexo-concave spring washer 24 having a notched edge is disposed on the shank 20 between the nut 21 and the head 15 of the boss 26 and limits the inward movement of the pawl 19 in response to the actuation of a 45 compression spring 25 that is coiled about the shank 20 within the confines of the tubular boss 14. The nut 21 can be tightened to expand the spring washer 24 more or less and thereby to permit the pawl 19 to move a 50 greater or less distance toward the center of the head of the lever to respond to the actuation of the spring 25. The extending inner end of the pawl 19 is beveled as indicated at 55 26 and is adapted to enter into one of the sockets 5 in the ratchet wheel 4 when the sections 8 and 9 are closed so that swinging of the lever in one direction about the axis of the shank of the jaw 1 will cause the screw 2 to turn in the same direction and swinging 60 of the lever in the opposite direction about the axis of the shank will not cause rotation of the screw 2 for the reason that the beveled face 26 of the pawl 19 will contact with a side wall of the associated socket 5 and will 65 ride out of such socket against the action of

the spring 25 onto the periphery of the ratchet wheel 4. In tightening the jaws, the lever will be arranged on the ratchet wheel 4 so that it will be effective to turn the screw 2 as required to move the jaw 1 in closing direction and the lever then may be reversed on the ratchet wheel when it is desired to open the jaws. Some suitable means such as the cross pin shown in Figures 2 and 3 is preferably used to retain the locking ring 13 on 70 the handle. 75

The specific structural form of the invention disclosed herein while representing a preferred form thereof is intended as illustrative rather than restrictive and modification and structural changes adapting the device to different operating conditions is contemplated in consonance with the spirit of the invention and the scope of the appended claims. 80 85

What I claim therefore, and desire to secure by Letters Patent is:—

1. The combination with a ratchet wheel having a circumferentially extending series of sockets in its periphery of a ratchet wheel operating member comprising a handle having an integral arcuately curved head section at one end thereof, a second arcuately curved head section having its shank pivotally connected with said handle, said shank being adapted to enter a cut away portion of said handle, a latching ring slidable on said handle to and from position to overlap said shank and then to maintain said head sections closed, said head sections being adapted when closed to embrace said ratchet wheel, one of said sections having a radial opening, and a tubular boss at the outer end of said radial opening, said tubular boss having a head at its outer end provided with an extending marginal edge portion, said edge of the tubular boss having an opening of restricted area in radial alinement with said first named opening in the wall of said head section, a pawl slidable in said first named radial opening and having a shank slidable in the opening in the head of said tubular boss, a compression spring within said tubular boss, between the head of the tubular boss and the outer end of said pawl, an adjusting nut on 105 the outer end portion of the shank of the pawl, and a spring washer between said adjusting nut and the head of said tubular boss, said adjusting nut having an outwardly extending finger formed with a bent end portion in contact with the outer edge of the head of said tubular boss. 110

2. The combination with a ratchet wheel having a circumferentially extending series of sockets in its periphery of a ratchet wheel 125 operating member comprising a handle having an integral arcuately curved head section at one end thereof, a second arcuately curved head section having its shank pivotally connected with said handle, said shank 130

- being adapted to enter a cut away portion of said handle, a latching ring slidable on said handle to and from position to overlap said shank and then to maintain said head sections closed, said head sections being adapted 5 when closed to embrace said ratchet wheel, one of said sections having a radial opening and a tubular boss at the outer end of said radial opening, said tubular boss having a head at its outer end provided with an extending marginal edge portion, said edge of the tubular boss having an opening of restricted area in radial alinement with said first named opening in the wall of said head 10 section, a pawl slidable in said first named radial opening and having a shank slidable in the opening in the head of said tubular boss, a compression spring within said tubular boss, between the head of the tubular 15 boss and the outer end of said pawl, an adjusting nut on the outer end portion of the shank of the pawl, and a spring washer between said adjusting nut and the head of said tubular boss, said adjusting nut having an outwardly extending finger formed 20 with a bent end portion in contact with the outer edge of the head of said tubular boss, said sections of the head of said ratchet operating member having side edge portions 25 extending along the sides of the peripheral portion of the ratchet wheel when said sections of the head of the operating member are disposed in embracing relation to said ratchet wheel. 30
3. The combination with a ratchet wheel, of a bodily detachable sectional arcuate wheel-embracing head, a spring pressed pawl housed therein, said head comprising one arcuate section having a rigidly connected handle extension, and a second arcuate section pivotally mounted at one end on said handle extension, and means for detachably locking 35 said second section to said handle extension in cooperative wheel embracing relation to said first arcuate section. 40
4. The combination with a ratchet wheel having a circumferentially spaced series of ratchet surfaces, of a bodily detachable handle wheel embracing head, a spring pressed pawl housed therein having a beveled ratchet 45 engaging surface effective to rotate said ratchet wheel in one direction of movement and sliding over said ratchet surfaces in the reverse direction of movement, said head comprising one arcuate section having a rigidly connected handle extension and a second arcuate extension pivotally mounted at one end on said handle extension, with means on 50 said handle extension movable to and from a position detachably locking said second section to said handle extension in cooperative wheel-embracing relation to said first section. 55
5. The combination with a ratchet wheel having a circumferentially spaced series of ratchet surfaces, of a bodily detachable 60
- wheel-embracing head, a cooperating pawl housed therein, said head comprising an arcuate section having a handle portion extending therefrom and slotted longitudinally and outwardly from its junction with said section, and a second arcuate section having an arm extending therefrom and housed in the slotted portion of said handle and pivoted intermediate of its ends therein, said arm being movable with its section on said pivot 65 from a wheel embracing position within said slot, to an expanded position without said slot permitting bodily removal of the head from the ratchet wheel, and means for detachably locking said arm within said slot with 70 said arcuate sections in contracted wheel embracing relation. 75
6. The combination with a ratchet wheel having a circumferentially spaced series of ratchet surfaces, of a wheel embracing head, a cooperating spring pressed pawl housed therein, said head comprising one arcuate section having an integral operating handle extending therefrom and slotted at its junction with said section, and a second arcuate section having an arm extending therefrom and pivotally mounted in said handle slot for movement from a position wholly within 80 said slot positioning its arcuate section for cooperation with said first section to embrace the ratchet wheel to a position without said slot permitting bodily withdrawal of the head from the ratchet wheel, and means on said handle movable to and from a position holding said arm wholly within said slot. 85
